UNITED STATES PATENT OFFICE.

NATHANIEL CRANK, OF HILL CITY, KANSAS.

APPARATUS FOR VAPOR-BATHS.

SPECIFICATION forming part of Letters Patent No. 445,464, dated January 27, 1891.

Application filed June 21, 1890. Serial No. 356,269. (No model.)

To all whom it may concern:

Be it known that I, NATHANIEL CRANK, a citizen of the United States of America, residing at Hill City, in the county of Graham and 5 State of Kansas, have invented certain new and useful Improvements in Apparatus for Vapor-Baths; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to medical apparatus designed for vapor-baths; and it consists in the improved construction hereinafter described and set forth, whereby a simple and efficient arrangement is provided wherein a 20 person may be properly subjected to the beneficial effects of a vapor-bath and the appliances for securing which are simple and durable.

In the accompanying drawings, forming 25 part of this specification, Figure 1 is a sectional view of my improved vapor-chamber, showing the relative position of the same with respect to the vapor-generator. Fig. 2 is a 30 plan view of the vapor-chamber. Fig. 3 is a detail view illustrating the employment of the improved platform.

The vapor-chamber consists of the base having rigid sides A A, the vertical end beams a of which are vertically grooved to receive the 35 rabbed edges b of the vertically-removable front B and back B'. Studs c, located on the beams a, are designed to be engaged by hooks d on the side and back to lock these sections in position.

40 The base comprises the bottom proper C, above which, within the chamber, is located a false bottom C', perforated in order that the liquid of condensation may pass to the space beneath, and be finally withdrawn therefrom 45 through a discharge-outlet e, located in the bottom C. This latter has corner-legs to maintain it the desired distance from the floor.

Within the chamber and adjacent to the back is located a permanent rest D, while a 50 movable seat D', preferably of the adjustable type, is also located in said chamber.

The top portion of the chamber inclines upward toward the front, and the several sides, back, and front are provided on their inner surfaces, near their top edges, with ledges f, 55 upon which rests the top or cover E of the vapor-chamber, so that it is snugly flush with the top edges of the side, back, and front. For the sake of convenience this cover E is made in front and rear sections hinge-connected, as shown, the former being provided with a ring or handle g, by which it may be raised or lowered, and said front section is also provided with an aperture h, through which the head of a patient may protrude, 60 the escape of vapor being prevented by wrapping a cloth or towel around the neck of the patient to form a vapor-tight joint around the neck.

Adjacent to the aperture h a vertical slot i 70 is made in the front section, and through this plays a vertical bar F, having a series of transverse perforations, so that the position of the bar can be vertically adjusted and held in any of its several positions by means of a 75 pin j passed transversely through one of the perforations therein and bearing on the top of the cover. This bar F carries at its upper end a loop k, which not only clamps a section l of rubber tubing to the metal tube m of a 80 flaring funnel G horizontally oval, but also supports said funnel, so that the tube l, which passes through the top, can take vapor from the chamber and deliver it to the funnel G, which is to rest over the mouth of the patient 85 in order that he may inhale vapor.

To maintain the funnel closely over the mouth, the frame is provided with an elastic band n, adapted to clasp the head of the patient and hold the funnel properly in position. 90

The vapor is generated in a boiler H, which is shown in Fig. 1, and consists of a light metallic receptacle designed to rest on a stove. This boiler is provided at its top with a nozzle closed by a cap o, and through which the 95 liquid to be converted into vapor is introduced. A cock p at one side permits the vapor to be blown off when necessary, and also enables the attendant to ascertain whether the liquid is passing into vapor. Centrally 100 the top of the generator is provided with an elbow-pipe q, with which the connection of the

flexible tube *r* is made to lead the vapor to the chamber.

As the rest and chair are shown in Fig. 1, they are adapted for the patient while in a sitting attitude. When a partially-recumbent position is desirable, it can be provided for by placing the perforated platform *I* so that its lower feet or supports will bear upon the rest and seat. This platform, as shown, consists of an extended horizontal plate of reticulated material, having its depending sides for strength, and bent inward so as to run off the condensation, and on the underside at each end a cross-brace *t* is provided to strengthen the plate and provide a connection for the feet. The top edges of the sides have turn-buttons *u*, adapted to pass above the top and retain it immovably in position.

In practice either the side or back is removed, so that the patient may enter and be seated in the chamber, after which the lid can be adjusted so that the head will be above the same. The hinged character of the lid makes it unnecessary to entirely remove the same when the patient enters from the front, as the hinged front section of the lid can be readily lowered, so that the head will pass through the aperture therein. In event of the patient being weak, the platform *I* can be used as a litter, and the patient seated on the

same can be moved into the chamber, the removable ends contributing to the convenience of this operation.

A thermometer *J*, located in one side of the chamber, indicates the temperature within 35 the chamber.

Having thus described my invention, what I claim as new, and desire to protect by Letters Patent, is—

In an apparatus for vapor-baths, the combination of the vapor-chamber having the perforated false floor, discharge beneath the same, and vertical recessed corner-beams *a*, end sections vertically sliding in said beams, and securing devices, a lid comprising hinged sections, one of which is perforated for the passage of the head of the occupant, a flexible tube communicating with the interior of the chamber and provided externally with a mouth-piece and clamps, and an adjusting-bar 40 for said mouth-piece secured in the lid, as described, together with a vapor-generator communicating with the vapor-chamber, substantially as set forth.

In testimony whereof I affix my singnature in presence of two witnesses.

NATHANIEL CRANK.
